CLOSURE STOP

Leonard H. Read, Hoxsie, R. I.

Application June 3, 1954, Serial No. 434,105

3 Claims. (Cl. 217—60)

This invention relates to closure stops for hinged members and more particularly to improved supporting means for a hinged cover such as, a hatch cover, bulkhead box cover, automobile hood, record player cabinet cover and the like.

An object of the present invention is to provide a superior hinged cover supporting means which will retain a cover in closed position, partially opened position or fully opened position.

Another object of the present invention is to provide a superior hinged hatch cover supporting means which when the cover is closed does not protrude below the level of the base of the hatch.

Another object of the present invention is to provide a hinged hatch cover supporting means which will automatically close when stepped on when the hatch cover is in partially opened position.

And still another object of the present invention is to provide a hinged escape hatch cover supporting means which will permit a small child to move the escape hatch cover from closed to open position.

Other objects of the present invention will become apparent in part and be pointed out in part in the following specification.

In the past hinged cover supporting means permitted covers to be held in open or closed position and not in an intermediate position. When used on a boat, the supporting means extended below the base of the hatch so that the danger of head injury was always present.

The supporting means included a spring held leverage which required great strength to overcome when changing the position of the cover from closed to open position. This condition negated the usefulness of an escape hatch for a child or injured person. The present invention overcomes these undesirable limitations.

Referring to the drawings wherein like reference characters refer to like parts.

Figure 1 is a perspective view showing the new and improved closure stop.

Figure 2 is a front elevational view of the same.

Figure 3 is a side elevational view showing the new and improved closure stop with the hatch cover in closed position.

Figure 4 is a view similar to Figure 3, showing the hatch cover in partially opened position.

Figure 5 is a view similar to Figure 3, showing the hatch cover in fully opened position.

The exemplary embodiment of the invention illustrated in Figures 1 through 5 is used in conjunction with the hinged cover of a bulkhead comprising a box frame 11 to which a cover 12 is pivotally mounted by means of hinges 13 and 14.

Since the bulkhead shown herein is merely for the purpose of illustrating an embodiment of the invention, other structural details of the bulkhead not essential to an understanding of the present invention are omitted.

The invention relates in particular to supporting means for the hinged cover 12, two such supporting means

2

being provided, as indicated generally at 16—16, each connected to the inner wall of the respective side of frame 11 by means of a bracket 15 and to the underside of the cover 12 by means of a bracket 17 and each comprising a linkage embodying a relatively long lever arm 18 provided with an elongated slot 20 in one end, a shorter lever arm 21 and two coil springs 22 and 23.

The upper end of lever arm 18 is pivotally secured as at 24 to bracket 17. The lower end of lever arm 21 is pivotally secured as at 25 to bracket 15. The opposite end of lever arm 21 is provided with a lug 26. Adjacent that end a stud 27 is fixed in the body of lever arm 21 and it extends beyond the body on either side so that one end of springs 22 and 23 can be fixed to stud 27 on opposite sides of the lever arm 21. The other end of springs 22 and 23 are fixed to a stud as at 24. Stud 27 rides in elongated slot 20 pivotally uniting lever arm 18 with lever arm 21 and constituting the fulcrum point of the linkage.

As shown in the drawing, the brackets 17 pivotally mounting lever arms 18 at 24 are secured to the underside of the cover 12 adjacent the edges of its opposite sides respectively and substantially to the rear of midway of its front and rear edges, while brackets 15 pivotally mounted lever arm 21 at 25 are fastened to the inner walls of the corresponding side panels of frame 11 of the bulkhead adjacent the upper forward end portions thereof. Thus, when the cover is in its normal closed position, as shown in Figure 3, lever arms 18 and 21 lie encased in the space above the lower edge of frame 11 and the underside of cover 12.

The stud 27 of the fulcrum point being at its extreme limit in elongated slot 20 produces maximum tension on springs 22, 23. On raising the cover 12 as indicated in Figures 1, 2, 4 and 5, the short lever arms 21 of the linkages swing upwardly carrying the studs 27 of the fulcrum points upwardly, while the long lever arms 18 remain almost parallel with the cover 12 thereby permitting the rounded edges of short lever arms 21 to contact the underside of cover 12 and hold it in partially opened position. Stud 27 of the fulcrum point is now located in the opposite end of elongated slot 20. The springs 22, 23 are in minimum tension position. Metal plates 30 may be secured to cover 12 to provide tracks for lever arms 21 to ride across.

Further movement of the cover upwardly draws lever arms 18, 21 into a straight line with lugs 26 abutting long lever arms 18, thereby limiting the pivotal movement of short lever arms 21. The upward movement of the cover 12 merely causes short lever arms 21 to pivot around stud 27, the fulcrum point with the stud 27 remaining in the end of elongated slot 20 and springs 22, 23 remaining in minimum tension position.

To close the cover 12, stud 27 at the fulcrum point must be manually pushed to cause short lever arms 21 to pivot around point 25 lifting lugs 26 away from long lever arms 18 until the rounded surface of short lever arms 21 contact plate 30. Further pressure on the cover will cause stud 27 to ride the length of elongated slot 20, thereby tensioning springs 22, 23 until the cover 12 engages frame 11, closing the hatch.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

What I claim is:

1. A closure stop for a cover hinged to a frame comprising a long lever arm and a short lever arm, means for

pivottally mounting one end of said long lever arm and one end of said short lever arm to said cover and frame, respectively, said long lever arm having an elongated slot, means on said short lever arm to pivotally engage said elongated slot and resilient means engaging said short lever arm to urge the free end of said short lever arm toward the pivotal point of said long lever arm.

2. A closure stop for a cover hinged to a frame comprising a first bracket provided with a first stud, fastened to said cover, a second bracket provided with a second stud, fastened to said frame, a long lever arm having an elongated slot in one end is pivotally mounted on its opposite end to said first stud, a short lever arm having a lug in one end is provided with a third stud fastened in and extending beyond one side, said short lever arm is pivotally mounted on its opposite end to said second stud with said third stud engaging said elongated slot and resilient means interposed between said first and said third stud.

3. A closure stop for a cover hinged to a frame comprising a first bracket provided with a first stud, fastened

5

10

20

to said cover, a second bracket provided with a second stud, fastened to said frame, a long lever arm having an elongated slot in one end is pivotally mounted on its opposite end to said first stud, a short lever arm having a lug in one end is provided with a third stud fastened in and extending beyond either side, and is pivotally mounted on its opposite end to said second stud with said third stud pivotally engaging said elongated slot and two coil springs, one on either side of said long lever arm, fastened on one end to said first stud and on the other end to said third stud.
